Attorney

UNITED STATES PATENT OFFICE.

MORRIS KALK, OF TULSA, OKLAHOMA.

BELT BUCKLE.

Application filed May 4, 1923. Serial No. 636,700.

To all whom it may concern:

Be it known that I, MORRIS KALK, a citizen of the United States, and resident of Tulsa, in the county of Tulsa and State of Oklahoma, have invented certain new and useful Improvements in Belt Buckles, of which the following is a specification.

This invention relates to certain new and useful improvements in the construction of belt buckles and the primary purpose of the invention is to provide a buckle of simple and inexpensive construction embodying means for holding the same in a fixed position on the belt so that objectional slippage of the buckle while in use is effectually eliminated.

Other purposes and advantages of the invention not specifically stated above will become apparent from the following detailed description and accompanying drawings, in which—

Fig. 1 is a perspective view of a belt having my improved buckle applied thereto.

Fig. 2 is an edge view of the construction shown in Fig. 1.

Fig. 3 is an end side elevational view of the belt and buckle disclosed in Fig. 1.

Fig. 4 is a fragmentary longitudinal sectional view.

Referring more particularly to the drawings, 5 designates a belt of conventional form provided adjacent to the end 6 with guide loops 7 adapted to receive the remaining end 8 of the belt therethrough, the said end 6 being provided with a metal loop 9 adapted to be engaged over a curved hook member 10 carried by the front plate 11 of my improved buckle and passing through an opening 12 formed in the end 8 of the belt. The said front plate 11 of the buckle has the side or longitudinal edges thereof

turned inwardly to provide flanges 13 and 14 adapted to overlie the corresponding edges of the belt 5 and these flanges are interconnected adjacent one end by a transverse guide bar 15, the aforementioned curved hook 10 being positioned adjacent the opposite ends of the flanges.

As herein shown the end 7 of the belt is provided with a series of openings 12 and 50 that the curved hook 10 of the buckle may be engaged with a selected one of said openings by moving the buckle longitudinally of the belt in an obvious manner. By reason of the fact that the curved hook 10 55 passes through the material of the belt, it will be evident that the buckle is held against any possibility of slippage such as frequently occurs with detachable buckles of this type. The curved hook 10 is further held against any possibility of withdrawal 60 through the opening 12 in which it is engaged by reason of the loop 9 intervening between said hook and the inner surface of the belt.

Having thus fully described my invention, what I claim as new and desire to secure by Letters Patent is:

The combination with a belt provided with a metal loop at one end and with a 70 longitudinally extending series of apertures at the opposite end, of a buckle adapted to receive the apertured end of the belt therethrough and provided with a hook member adapted to pass through a selected 75 one of the said apertures and to be engaged through the said loop to secure the ends of the belt together.

In testimony whereof I hereunto affix my signature.

MORRIS KALK.
